UNITED STATES PATENT OFFICE.

ARTHUR E. PECK, OF MINNEAPOLIS, MINNESOTA.

BICYCLE-SADDLE.

SPECIFICATION forming part of Letters Patent No. 599,729, dated March 1, 1898.

Application filed September 7, 1895. Renewed November 2, 1897. Serial No. 657,207. (No model.)

To all whom it may concern:

Be it known that I, ARTHUR E. PECK, a citizen of the United States of America, residing at Minneapolis, in the county of Hennepin 5 and State of Minnesota, have invented a certain new and Improved Bicycle-Saddle, of which the following is a specification.

The object of this invention is to provide an improved bicycle-saddle consisting, preferably, of separate sections, one or more of said sections being provided with a pneumatic pad or cushion; and the invention consists generally in the constructions and combinations hereinafter described, and particularly pointed out in the claim.

In the accompanying drawings, forming a part of this specification, Figure 1 is a plan view of a bicycle-saddle constructed in accordance with my invention. Fig. 2 is an under side view of the saddle. Fig. 3 is a longitudinal vertical section on the line *y y* of Fig. 2.

In the drawings, 2 represents the frame or support for the rear or main section of the seat. This is of any convenient size and shape, and it is provided with means to support the forward or yielding sections.

In Figs. 1, 2, and 3 I have shown the section 2 provided with an ordinary upholstered surface, said section being secured upon the seat-post 5 by means of the lugs 6 and the projections 8 from the sides of said post. Suitable screws 10 are provided upon the lugs 6 for the purpose of securing said section at any desired angle upon the seat-post. Secured upon the under side of the section 2 are the arms 21, which project forward from the forward edge of said section 2. These arms support the pneumatic cushion, bag, or pad 29, which preferably extends across the

full width of the section 2 and forms yielding forward sections for the said saddle. This pad is preferably made all in one piece, but at the center it is provided with the arm 23, extending over its upper surface, and said arm forms a partial division between the two sections by partially contracting the pad at the central line, so that when in operation the rider from the reciprocating movement of his legs presses downward first upon one section 45 of the pad and then upon the other the downward pressure upon one section forces the air out of that section into the other, causing such section to move upward, following the movement of the rider's leg. Upon the reverse movement the opposite action takes place. If preferred, the rear section 2 may also be provided with a pneumatic pad.

The details of construction may be modified without changing the principle of the invention.

I claim as my invention—

The combination, in a bicycle-saddle, of the rear plate or section, with the forward independent sections comprising pneumatic pads, a suitable duct being provided between said pads, said pads containing together substantially enough air to fill one of them, whereby as the surface of one pad is depressed the air will be forced therefrom into the other 65 pad to raise the upper surface thereof, substantially as described.

In testimony whereof I have hereunto set my hand this 4th day of September, A. D. 1895.

ARTHUR E. PECK.

In presence of—

A. C. PAUL,
B. P. SHEPHERD.
